SPRING HINGE

Godfrey E. Sundell, Ridgway, Pa.

Application April 28, 1939, Serial No. 270,533

3 Claims. (Cl. 16—149)

This invention relates to spring hinges and is directed particularly to detachable locking hinges for screen doors, storm windows and the like which are ordinarily removed during different seasons of the year.

Detachable locking hinges for a similar purpose are old in the art but to the best of my knowledge, these hinges as ordinarily constructed require an additional element to secure or lock the hinge to a door or window frame. The principal object of my invention is to overcome the necessity for additional locking elements and provide a hinge having a minimum number of parts constructed in a manner to be readily attached to a securing frame or removed therefrom without necessitating the use of screws or other securing devices. Another object of the invention is to perform one or both hinge leaves in a manner to provide locking elements therein. Still another object is to provide a novel spring and pintle connection for the hinge leaves.

In the accompanying drawing, Fig. 1 is a fragmentary sectional view showing a door secured to its frame with the hinge locked to each member. Fig. 2 is a plan view of a hinge keeper plate. Fig. 3 is a plan view of a butt or strap hinge in open position. Fig. 4 is a sectional view on the line 4—4 of Fig. 3 showing the spring and pintle arrangement.

Referring to the drawing wherein similar parts will be indicated by like numerals, 10 shows a door frame having a recessed portion 11 which is covered by a keeper plate 12 permanently secured to the frame by suitable screws. The keeper plate 12 is provided with apertures 13 giving access to the recess 11. A door 14 is likewise provided with a recessed portion 15 which is similarly covered by a keeper plate 12 of the same design as that used on the door frame which is permanently secured thereto and provided with apertures giving access to the recess 15.

The hinge is formed of the leaves 16 and 17, shown in Fig. 3, which are pivoted together by means of interlocking sleeves 6 and 7 formed on one edge of each leaf 16 and 17 respectively while the opposite edges of the leaves are provided with lugs 19 and 20 respectively which are cut out of the leaf bodies. As shown clearly in Fig. 1 the lugs 19 and 20 are bent outwardly substantially at right angles from the leaf body providing shoulders 21 and then are bent again in the same direction substantially at right angles to provide shoulders 22 and connecting portions 23 between the shoulders which are approximately as wide as the slotted portions 13 and adapted to fit therein.

The ends 24 of each of the lugs is then bent towards the body of the leaves to be conveniently received in the recesses 11 and 15. In securing the door 14 to its frame 10 the ends 24 of the lugs 20 on the leaf 17 are inserted in the slots 13 of the frame keeper plate at an angle thereto and the leaf is urged toward the frame until parallel therewith which forces the shoulders 21 and 22 in substantial engagement with the edges formed by the slots 13 thus providing a locking connection. Similarly the ends 24 of the lugs 19 on leaf 16 are inserted in the slots of the door keeper plate and the shoulders 21 and 22 forced to engage the edges formed by the slots 13 to lock this leaf to the keeper plate.

To remove the hinge or to detach one or both leaves from the keeper plates it is only necessary to pull the hinge leaves from the keeper plates and break the locking connections which may be readily accomplished by inserting a wedge between the leaf bodies and forcing the door 14 toward the frame. This is readily done by partly opening the door 14 and spreading the hinge leaves 16 and 17 and then inserting a screw driver or some suitable tool between the leaves at a point adjacent the hinge sleeves. By urging the door to its frame after the wedge is inserted the lugs 19 or 20 may be easily pulled out of the apertures 13 in the keeper plates. When it is desired to attach the door to its frame, the leaves 16 and 17 are similarly spread and held apart by a wedge in order to permit the lugs 24 of the leaves to be inserted in the slots 13 of the keeper plates and the shoulders 21 and 22 forced to abut and form a locking connection with the slots 13 of the keeper plates.

In Fig. 4 is shown a novel spring connection for the hinge leaves which is inexpensive, efficient and easily assembled. The end pintle sleeves 6 and 7 of the leaves are held together by means of pins 30 which are securely held by the sleeves 6 and rotatable in the sleeves 7. Coil springs 31 and 32 are disposed between the pins 30 and have their outer ends 25 and 26 respectively held by suitable slots in the sleeves 7 and their inner ends 27 and 28 respectively held by suitable slots in the central sleeve 6.

Cooperating pintles or spring retaining members 33 and 34 extend centrally of the springs and are provided with heads 35 and 36 respectively which act as stops for the outer ends of the springs to prevent binding against the pins 30. The inner ends of the pintles when assembled abut in order to give rigidity and greater strength.

to the assembly and provide for simplicity in assembling the device.

It will be apparent from the foregoing description taken in connection with the single embodiment of the invention shown in the drawing that I have provided a spring hinge which is simple in construction and adapted to a variety of uses.

I claim:

1. A hinge comprising a pair of pivoted leaves, a locking lug on at least one of said leaves, said lug having a connecting portion extending from the leaf body substantially at a right angle thereto, a central portion extending from the connecting portion to form a right angled shoulder therewith, said central portion lying substantially parallel to and out of the plane of the leaf body, an upwardly extending portion forming a right angled shoulder with the central portion, and a free end portion extending at an angle away from the upwardly extending portion and lying out of the plane of the leaf body and central portion, in combination with a plate having a slot therein for receiving the central portion of the lug in locking engagement with said right angled shoulders.
2. A hinge comprising a pair of hinge leaves having cooperating aligned sleeves, pintle means extending through said sleeves providing a pivotal connection, lugs on said leaves, each lug having

a connecting portion extending substantially at a right angle to the leaf body, a central portion disposed at a right angle to the connecting portion and extending away from the pivotal connection, said central portion substantially parallel to and out of the plane of the leaf body providing with the connecting portion a locking shoulder, an upwardly extending portion forming a substantially right angled locking shoulder with the central portion, and a free end portion extending at an angle away from the upwardly extending portion, in combination with means for receiving the central portion of the lugs and locking the hinge leaves in fixed position.

3. A hinge comprising a pair of hinge leaves having cooperating aligned sleeves, pintle means extending through said sleeves providing a pivotal connection, lugs on said leaves, each lug having a connecting portion extending substantially at a right angle from each leaf body, a central portion extending at a right angle from the connecting portion and substantially parallel to and out of the plane of the leaf, an upwardly extending portion forming a right angle locking shoulder with the central portion and a free end portion extending at an angle away from the upwardly extending portion to be disposed out of the plane of said central portion and leaf body.

GODFREY E. SUNDELL.
